UNITED STATES PATENT OFFICE

ROBERT H. FIDLER, OF NORTH ARLINGTON, NEW JERSEY, ASSIGNOR TO TUNG-SOL LAMP WORKS, INC., OF NEWARK, NEW JERSEY, A CORPORATION OF DELAWARE

RADIOTUBE

Application filed June 18, 1930. Serial No. 461,946.

This invention relates to radio tubes.

One object of the invention is a tube having an insulating plate mounted upon and supported directly by the anode supporting posts in a novel and improved manner, and a further object is a tube of this general character wherein the tension and anchor hook for the filament is supported by the insulating plate and assembled thereupon and fastened thereto in a manner to facilitate the assembly and to assure uniform tensioning and spacing of the filament. Another object of the invention is a tube having an insulating plate with metallic eyelets formed and mounted therein for the accommodation of the anode and anchor supports and for fastening the plate thereto by welding the supports to the eyelets in the exact and adjusted position desired. A further object is a tube structure wherein the filament tension hook or hooks and anchor supports are formed as units and then assembled, adjusted and fastened upon the insulating plates by welding the supports to eyelets formed in the plates in the position desired.

For a better understanding of the invention reference may be had to the accompanying drawing forming a part of this application wherein:

Fig. 1 is a perspective view of a radio tube embodying the invention with a part of the bulb broken away,

Fig. 2 is a plan view of a part thereof,

Fig. 3 is a plan view corresponding to Fig. 2 showing a further step in the manufacture,

Fig. 3a is a perspective view of an eyelet utilized in the construction,

Fig. 4a is a perspective view showing another step in the assembly,

Fig. 4b is a perspective view showing another step in the assembly,

Fig. 5 is a view showing the method of tensioning the filament hook and fastening the hook support to the insulating plate, and

Fig. 6 is a perspective view of a part of a modified form of tube embodying the invention.

Referring to the drawing I have shown my invention as embodying a radio tube having a plate 1, plate support posts 2, grid 3, fila-

ment 4 and a plate 5 of mica or other insulating material mounted at the top of the tube elements. The plate 5 blank may be formed, as indicated in Fig. 2, according to any desired practice, this plate having holes or openings 6 for accommodating the plate support posts 2 and similar holes or openings 7 for the reception of the filament anchor hook supports. The holes 6 and 7 of the blank of Fig. 2 are then provided with metallic eyelets as for example of the character indicated in Fig. 3a, these eyelets being designated generally by the numeral 8 and having a flange 9 engaging one side of the plate and tubular part 10 passing through the hole or opening to the other side of the mica plate. The tubular parts 10 include tongues 11 which may be bent or peened over to anchor the eyelet in the opening as indicated in dotted lines in Fig. 3a. The method of assembly and attachment of the plate 5 is indicated in Fig. 4a. The plate 5 of Fig. 3 is inserted over the posts 2, the latter projecting into or through the eyelets 8, and after the insulating plate is adjusted to the required position the eyelets 8 are joined to the posts 2 in any suitable manner, as for example by spot welding. With the plate thus adjusted and fastened to the posts 2 to be rigidly supported thereby the grid posts 3' pass up through guide slots 12 formed in the plate 5 in the usual manner, as indicated in Figs. 1 and 4b.

The next step in the assembly is the mounting of the filament tension hooks 13 with the anchor support posts 14 upon the insulated plate. The tension hook and anchor wire 13 is fastened to the anchor post 14, as for example by spot welding, into a unitary structure with the hook disposed at a fixed distance from the post 14 or in other words the anchor wire being cut to a predetermined length and welded to the post 14 prior to the mounting upon the insulating plate. This length is predetermined in the stamping of the blank of Fig. 2 and the openings 7 therein. The unit consisting of the anchor wire 13 and the anchor support 14 is then positioned upon the plate 5 with the post 14 projecting down through the eyelet 8 within the opening 7

formed in the plate and by adjusting the post 14 up and down the exact tension desired for the filament 4 may be readily obtained and in that position the post 14 is fastened to the eyelet 8, as for example by spot welding, the distance between the dot and dash lines and the full line illustration of the anchor wire 13 of Fig. 5 indicating the approximate adjustment from one position to the other. 10 In the particular embodiment shown in Figs. 1 to 5 there are two filaments 4 and two anchor units for tensioning the filaments.

The modification of Fig. 6 shows a slightly different type of tube wherein the two anchor 15 posts 15 carry two separate and independent plates 16 with a filament 17 in each oval shaped plate. The insulating plate as for example 18 is mounted upon and attached to the posts 15 in the same manner as is the plate 20 5 upon the posts 2 above described. Also the anchor and tension hook 13 and the post 14 units are mounted upon the plate 18 in exactly the same manner as these units are mounted in the other modification described above.

25 By means of this construction the mica plates may be accurately positioned and firmly fastened to the support posts with marked facility and with a minimum of time and at minimum expense. Moreover, the filaments are accurately and uniformly tensioned with the proper spacing thereof by means of the construction and method of construction set forth, and in addition to a more satisfactory product of more uniform 30 35 quality the manufacture and production of the tube are greatly facilitated.

I claim:

1. A radio tube including a filament, a pair of supporting posts, an insulating spacer 40 disk having eyeleted openings for the accommodation of and attachment to said posts, said disk having an additional eyeleted opening for the reception of an anchor support member and an anchor unit comprising an 45 anchor support member and an angularly disposed tension wire hook member of predetermined length fastened to the support member intermediate its ends, said unit being adjustable lengthwise of said support member in said last named eyeleted opening with the hook member engaging the filament for 50 adjusting the tension during the operation of fastening the member to the eyelet of the opening.

55 2. A radio tube as in claim 1 wherein the posts carry an anode plate and the insulating disk has guide and spacing slots for the reception of grid posts.

60 3. A radio tube as in claim 1 wherein the eyeleted openings of the insulating disk include hollow rivets with the sleeve part of the rivet having tongues which are peened over to hold the eyelets within the openings.

65 4. A radio tube including a relatively adjustable supporting post and an insulating

70 spacer disk, the latter having an eyeleted opening into which the post passes and to which the post is adjustably fastened, said opening being just large enough to accommodate said post.

5. In a tube as in claim 4 wherein the disk is anchored to the post by welding the eyelet to the post.

6. A radio tube including a filament, an insulating support having an eyeleted opening 75 for the reception of an anchor support member and an anchor unit comprising an anchor support member and an angularly disposed tension wire hook member of predetermined length fastened to the support member intermediate its ends, said unit being adjustable lengthwise of the support member in said last named eyeleted opening with the hook member engaging the filament for adjusting the tension during the operation of fastening the unit to the eyelet of the opening.

7. The method of making a radio tube which consists in positioning an insulating disk with eyeleted openings formed therein upon supporting posts and fastening the disk in position by adjusting it up and down upon the posts with the latter passing through the eyeleted openings and then welding the posts and the eyelets together, forming an anchor unit by fastening a tension hook of predetermined length to an anchor support, and then mounting the unit by inserting the support through an eyeleted opening in the insulating disk adjusting the same up and down to obtain the required filament tension and then welding the support to the eyelet in the opening.

8. The method of supporting an anchor hook and tensioning the filament of a radio tube which consists in positioning and anchoring an insulating support adjacent the filament forming an anchor unit by fastening a tension hook of predetermined length to an anchor support, and then mounting the unit upon said insulating support by inserting the anchor support through an opening therein, adjusting the unit up and down to obtain the required filament tension and then anchoring the unit to the insulating support in the adjusted position.

9. A radio tube of the character set forth in claim 6 wherein the eyeleted opening of the insulating support includes a hollow rivet with the sleeve part of the rivet having a tongue peened over to hold the eyelet within the opening.

In testimony whereof, I have signed my name to this specification.

ROBERT H. FIDLER.
